E. D. Kelly,

Attorney

UNITED STATES PATENT OFFICE.

FRANK H. HOWARD, OF READING, PENNSYLVANIA, ASSIGNOR TO READING CHAIN AND BLOCK CORPORATION, OF READING, PENNSYLVANIA, A CORPORATION OF PENNSYLVANIA.

LIMIT STOP FOR ELECTRIC HOISTS.

Application filed February 14, 1925. Serial No. 9,100.

To all whom it may concern:

Be it known that I, FRANK H. HOWARD, a citizen of the United States, residing at Reading, in the county of Berks and State of Pennsylvania, have invented certain new and useful Improvements in Limit Stops for Electric Hoists, of which the following is a specification.

This invention relates to a limit stop for electric hoists and the object is to provide a simple and effective device whereby the controller may be actuated automatically through the medium of a rod having means for determining predeterminedly the points at which the controller is to be affected to start or stop the device.

The invention in the present instance consists of a crank mounted on the frame of the winding drum, and interposed between the operating rod leading to the controller, and the movable member on the shaft of the winding drum, whereby the actuation of the rod is effected.

The invention is more fully described in the accompanying drawing and clearly illustrated in the accompanying drawing, in which:

Figure 1 is a plan view of a portion of a winding drum and its shaft, with my invention applied thereto.

Figure 2 is a front elevation thereof.

The numeral 1 designates the winding drum of a hoist and this is provided with a screw shaft 2 and on this shaft I place a nut 3, adapted to move when the shaft rotates. This nut is formed with an upstanding pin 4 which engages an elongated slot in one end of a crank 6. This crank 6 is mounted in a casing 7 on the frame of the machine and its lower extremity 9 is in engagement with and adapted to move freely

on, the end of a controller rod 11. This rod is provided with two movable members 12, capable of adjustment thereon, and contact with either of these members by the end of the crank member 9 will actuate the said rod, which is in engagement at its opposite end with the controller 15.

When the winding drum rotates, the nut 3 moves thereon, until the crank arm has moved sufficiently to engage one of the adjustable members 12, and the controller is then actuated.

The construction is extremely simple and its effectiveness is assured by said simplicity.

Having thus described the invention, I claim:

1. In a limit stop for electric hoists, the combination of a controller, a controller rod connected thereto, a winding drum, a screw threaded shaft for the drum, a nut on said shaft adapted to be moved by the rotation of the shaft, a pin on said nut, a crank having an elongated slot which engages said pin, and whose opposite end loosely engages the controller rod, and means in the form of adjustable nuts on said rod to determine the point at which the rod will be moved by the crank.

2. In a limit stop for electric hoists, the combination of a hoisting drum, a controller, a controller rod connected thereto, a screw-threaded shaft for the drum, a nut on said shaft, a crank arm mounted on the drum frame, one end of which is in engagement with said nut and the other with said controller rod, and adjustable means on the controller rod whereby the time of actuating the controller may be determined.

In testimony whereof I affix my signature.

FRANK H. HOWARD.
